(57) **CLAIM**

The ornamental design for a hat, as shown and described.

DESCRIPTION

FIG. 1 is a perspective view of the present invention;
FIG. 2 is a front elevational view of the present invention;
FIG. 3 is a right side elevational view of the present invention,
the left side elevational view being a mirror image thereof;
FIG. 4 is a rear elevational view of the present invention;
FIG. 5 is a top plan view of the present invention; and,
FIG. 6 is a bottom plan view of the present invention.
The broken lines in FIG. 6 represent features of the article of
manufacture that form no part of the claimed design.
